BRIDLE

Walter A. Bass, Brundidge, Ala.

Application November 13, 1945, Serial No. 628,087

5 Claims. (Cl. 54—6)

1

This invention relates to bridles, and is a continuation-in-part of my application Serial No. 591,929, filed May 4, 1945.

It has for its object to provide a bridle or head stall for horses and mules which is so formed and assembled with the usual or any desired bit that stitching of the straps that go to make up the bridle is done away with, and the entire assembly, insofar as head strap, cheek straps, blinders, and blinder or winder straps are concerned, may be conveniently assembled and adjusted by the use of a single buckle on each side of the bridle. With this novel arrangement repairs and replacements can be made without the necessity of the skilled labor of the harness maker, as anyone can assemble, disassemble, and replace worn parts by the simple expedient of unbuckling the bit ring engaging end of the bridle straps.

In the drawing herewith the bridle is illustrated in the single perspective view.

Referring to the drawings by numbers, 10 indicates the head strap provided with a front band 11 of not unusual shape, this front band being preferably secured to the head strap by means of the thong 12 passed through suitable openings in the double end 13 of the front band, the ends of the thong 12 preferably knotted and anchored at 14 in the rosette 15. Fastening means other than the thong may, if desired, be used.

The usual throat latch 16 may be provided, and this throat latch will be formed by cutting a strip 17 from one end of the head strap 10 so that an integral formation of head strap and throat latch is provided, one end of the throat latch 16 being preferably longer than the other end, and the ends being joined by a buckle 18, as shown. This integral construction of head strap and throat latch does away with the necessity of fastening the parts together by stitching or riveting, as is now common.

The cheek straps 19 are threaded through apertures 20 in the blinder. Four of these apertures are shown in the present instance, but it will be understood that they may be of any desired or needed number. The ends of the straps 19 passing through the bit rings 21 engage a buckle 22 which is held by a loop 23 of the head strap where it passes through the apertures 20 in the blinder.

The blinders 24 may be of any suitable shape and thickness, but it has been found that with the construction here shown, leather or other material of a thinner gauge can be used with good results, for the reason that the blinder is stiffened

by its assembly with the head strap ends. It is preferably slotted or notched at 25 providing an open slit in the top edge of the blinder to receive the front band 11 which tends to hold it in position. This slotted engagement of blinder 24 with the front band 11 so positions and holds the blinder that it cannot flap and strike the eye of the animal, which would result in discomfort to and possible injury of the animal's eye.

The blinders 24 are provided with extended bit ring engaging ends 26 which are lapped inside the buckle engaging ends of the cheek strap ends 19, and engage the buckle 22 with which the cheek strap ends are engaged, this buckle serving to hold the assembled cheek strap ends and blinder strap ends together, the buckle being of sufficient size to take the three plies of straps with which it is engaged. It will be seen that the end 26 of the blinder strap takes the wear of the bit ring 21 and the double thicknesses of straps supporting the bit rings provide a very secure bit support. The blinders, it will be seen, extend upwardly sufficiently to engage the front band with their open slits 25. This not only prevents, as heretofore pointed out, the blinder from flapping and striking the animal's eye, but also positions the blinders so that the animal cannot look backward over the top of the blinder, as frequently happens with the usual bridle construction. This habit sometimes results in scaring the animal and accidents occur.

The bridle may be readily and quickly converted to an open bridle, if it is desired to dispense with the blinders. All that is necessary to accomplish this is to unbuckle the end straps from the buckle 22, unthread the cheek strap ends 19 from the apertures in the blinder through which they pass, and then re-engage the ends 19 of the cheek strap with the buckle and provide an open bridle.

The advantages of this construction are that it is simple in its make-up and assembly. All of the parts may be quickly and readily cut from ordinary harness stock by following the simple pattern of the different pieces. The individual pieces can be quickly assembled without the necessity of stitching or riveting any of the parts together, it being necessary only to adjust the buckle which holds the parts together at the proper point, after which the strap ends may be passed through the bit rings, coupled to the buckle and the bridle is complete. The assembling of the head strap and the throat latch requires only the simplest of operations, involving as it does, only the threading of the straps through the

parts. All stitching, as stated, is eliminated, resulting in a bridle of longer life, as stitching is quickly attacked and rotted by sweat and constant repair work is necessary.

Such changes in details of construction as are within the skill of the mechanic and the scope of the appended claims may, of course, be made without departing from the invention.

I claim:

1. A bridle comprising a head strap, cheek straps extending from said head strap, blinders having strap openings through which the cheek straps are threaded, bit ring engaging ends on said blinders, and a buckle mounted on each cheek strap to receive and hold the cheek strap and blinder strap bit ring engaging ends.

2. A bridle comprising a head strap, cheek straps extending from said head strap, blinders having strap openings through which cheek strap ends are threaded, integral throat latching ends extending from said head strap, bit ring engaging ends on said blinders, and a buckle mounted on each cheek strap to receive and hold the cheek strap and blinder strap bit ring engaging ends in adjusted positions.

3. A bridle comprising a head strap, cheek straps extending from said head strap, a front strap, blinders having strap openings through which cheek strap ends are threaded and slotted at their tops to engage said front strap, integral throat latching ends extending from said head strap, bit ring engaging ends on said blinders,

and a buckle mounted on each cheek strap to receive and hold the cheek strap and blinder strap bit ring engaging ends in adjusted positions.

4. A bridle comprising a head strap, cheek straps extending from said head strap, a front strap, blinders having strap openings through which the cheek straps are threaded, said blinders being slotted at their upper ends to engage said front strap, bit ring engaging ends on said blinders, and a buckle mounted on each cheek strap to receive and hold the cheek strap and blinder strap bit ring engaging ends.

5. A bridle comprising a head strap, a front strap, cheek straps extending from said head strap, blinders having slits in their upper ends to engage said front strap, and bit engaging ends extending from said blinders.
